UNITED STATES PATENT OFFICE.

WILLIAM J. O'KEEFE, OF MILWAUKEE, WISCONSIN.

ENGINE.

No. 923,569.

Specification of Letters Patent.

Patented June 1, 1909.

Application filed September 28, 1908. Serial No. 455,091.

To all whom it may concern:

Be it known that I, WILLIAM J. O'KEEFE, a citizen of the United States, and resident of Milwaukee, in the county of Milwaukee and State of Wisconsin, have invented certain new and useful Improvements in Engines; and I do hereby declare that the following is a full, clear, and exact description thereof.

My invention consists in what is herein particularly set forth with reference to the accompanying drawings and pointed out in the claims of this specification, its object being simple, economical provision for keeping oil in the crank and crosshead casing of an engine from detrimental heating.

Figure 1 of the drawings represents a vertical, longitudinal section, as indicated by line 1—1 in Fig. 2, of a crank and crosshead casing of a horizontal engine provided in the oil-space thereof with a conductor through which to flow a cooling liquid, a portion of the engine-crank, cross-head and piston-rod being in elevation and the connecting-rod indicated by a dotted line; Fig. 2, a transverse section of the casing on the plane indicated by dotted line 2—2 in Fig. 1, and Fig. 3, a horizontal section of said casing on the plane indicated by line 3—3 in Fig. 2.

Referring by letter to the drawings, A indicates the crank and cross-head casing of a horizontal steam-engine. Arranged in the oil-space of the casing to be partly submerged by oil therein at normal level is a conductor, preferably in the form of a pipe-coil B, through which to flow a cooling liquid. Stretches of this pipe-coil form of conductor are shown extending parallel to the crosshead guide *h* in the casing, and inlet and outlet cocks *f*, *g*, are provided in connection with

said stretches of the coil outside of said casing.

In practice, oil from the casing A is splashed by the engine crank C onto the guides *h* to lubricate the cross-head D and thereafter find its way back into the deepest portion of said casing. Ordinarily, the aforesaid casing and oil therein become heated to such a degree as to be detrimental to said oil, but by running water or other cooling liquid through the conductor in the oil-space, as aforesaid, said oil is kept at a sufficiently low temperature, the area of cooling surface being variable to meet the requirements in various engines, and while I have shown my invention as applied to a horizontal cross-head engine, it is just as applicable to a vertical crosshead engine.

I claim:

1. An engine-crank and crosshead casing having a cross head guide, and a cooling liquid conductor that is contained in the oil-space of the casing and provided with stretches parallel to opposite sides of said cross-head guide in said casing.

2. An engine-crank and cross-head casing having a cross head guide, and a cooling liquid conductor in the form of a pipe-coil that is contained in the oil-space of the casing and has stretches thereof extending parallel to opposite sides of said cross-head guide.

In testimony that I claim the foregoing I have hereunto set my hand at Milwaukee, in the county of Milwaukee and State of Wisconsin in the presence of two witnesses.

W. J. O'KEEFE.
